UNITED STATES PATENT OFFICE.

EDWARD WILLIAM BROWN, OF HOLBORN, LONDON, ENGLAND.

MACHINE FOR INTERMITTENTLY DISPLAYING POSTERS AND THE LIKE.

1,132,910.

Specification of Letters Patent. Patented Mar. 23, 1915.

Application filed June 2, 1914. Serial No. 842,530.

To all whom it may concern:

Be it known that I, EDWARD WILLIAM BROWN, subject of the King of Great Britain, residing at 8 and 9 Gray's Inn Passage, Red Lion street, in the borough of Holborn, county of London, England, have invented certain new and useful Improvements in Machines for Intermittently Displaying Posters and the like, of which the following is a specification.

This invention relates to machines for intermittently displaying posters and the like, of the kind in which the poster is mounted on or forms a portion of a band, which is led across an aperture, before which the poster is held stationary and exposed to view, either the band being unwound from one roller and wound upon another the direction of winding being reversed when all the band has been paid out, or the band being endless and moving in a constant direction.

The chief feature of the present invention resides in the means for intermittently stopping and starting the band of posters, and consists in the circuit of the electro-motor, which drives the contrivance, having switches arranged in parallel, one of which is opened during the passage of a poster across the display aperture and the other switch being opened and stopping the motor when the poster has come into the displaying position, whereafter the first switch is closed on a delaying device eventually yielding, thereby again starting the motor and the band.

Another feature of the invention consists in the improved means for reversing the direction of rotation of the motor and travel 40 of the band, and for driving the winding roller and disconnecting from the motor the roller which is paying out the band.

An example of a machine according to the present invention is illustrated on the accompanying drawings, in which:

Figure 1 is a rear elevation, Fig. 2 a section showing the right hand side, and Fig. 3 a section showing the left hand side of the machine. Fig. 4 is an elevation of one of the 50 driving clutches on an enlarged scale. Fig. 5 is a fragmentary elevation showing the method of mounting the posters.

a is a band, of linen for instance, which is led from a roller b¹ over a guide roller c¹ at the bottom of the machine past an ex-

posure aperture and over a guide roller c² to a roller b² at the top of the machine, the band a being unwound from the one roller b¹ or b² and wound on the other b² or b¹, according to which roller is being driven.

The drive is effected by an electro-motor d, through a reducing gear e, the counter shaft e¹ of which has secured thereon a pair of sprocket wheels f. These sprocket wheels f are connected by pitch chains g¹, g² respectively to a sprocket wheel f¹ mounted free on the spindle of the lower roller b¹ and to a sprocket wheel f² mounted free on the spindle of the upper roller b². The boss of each sprocket wheel f¹, f² adjacent to the 70 respective roller b¹, b² is formed with a crown ratchet tooth f³ and the boss on the other side of each sprocket wheel f¹, f² is formed with an oppositely directed crown ratchet tooth f⁴. The teeth f³ and f⁴ of the 75 one sprocket wheel f¹ are oppositely directed to the corresponding teeth f³ and f⁴ of the other sprocket wheel f². Free on the spindle of each roller b¹, b² alongside each sprocket wheel f¹, f² is a sleeve h held frictionally by clamps i. These sleeves h each have a crown ratchet tooth h¹ directed to engage the corresponding teeth f⁴ of the 80 sprocket wheel f¹, f². On rotation of the counter shaft e¹ in a direction to cause the 85 roller b² to wind on itself the band a, the tooth f⁴ of the sprocket wheel f² rides along the incline of the tooth h¹ of the respective sleeve h because this latter is subjected to the drag of the brake clamps i, and the sprocket 90 wheel f² is displaced along the spindle toward the roller b², whereby the tooth f³ on the other side enters into engagement with a pin j. At the same time the tooth f³ of the lower sprocket wheel f¹ rides by its incline 95 against the pin j of the lower roller b¹ and is displaced toward the respective sleeve h, whereby its other tooth f⁴ enters into engagement with the tooth h¹ of this sleeve h and rotates the latter. By virtue of the drag 100 of the brake clamps i on the sleeve h and the teeth f⁴ and h¹ being undercut, the sprocket wheel f¹ is kept away from the roller b¹, until the direction of rotation is reversed, when the opposite series of operations occur.

The above arrangement insures that the roller b¹ or b² which is being unwound is disconnected from the driving mechanism, thus allowing it to rotate differentially as 110

- its effective diameter decreases due to the unwrapping of the band a therefrom.
- A one-way clutch disk k is mounted on the spindle of each of the rollers b^1 and b^2 at the 5 ends of the rollers remote from the sprocket wheels f^1 , f^2 . When the respective roller is paying out the band a the respective free-wheel disk k is carried around by the spindle, and as each disk k is permanently gripped between brake clamps k^1 , the 10 roller is subjected to a braking action which keeps the band a taut. When the roller rotates in the reverse or winding direction, its spindle rotates freely in the free-wheel 15 disk k , which therefore does not revolve, being held by the brake clamps k^1 , and no resistance is thereby imposed to the rotation of the roller.
- The motor d and band a are stopped and 20 after an interval re-started as follows:—A transverse slat l is mounted on the band a at the ends of each poster, the ends of the slats when passing across the machine, running in the grooves l^1 in each side of the 25 machine. During its passage across the machine, each slat l forces back a plunger rod m which through a bell-crank m^1 raises a weighted contact bar n^1 out of contact with a spring contact n^2 , these two contacts 30 being in a parallel circuit of one of the leads of the motor. The weighted contact bar n^1 is pivoted to a link n^3 and on its descent by gravity drives a clockwork train n^4 having a fan n^5 .
- 35 At the top and at the bottom of the machine a lever o is pivoted with one end in the path of the slats l . On one or the other of the levers o being displaced by a slat the other end of the lever o is moved out of 40 contact with a contact o^1 , in a second parallel circuit of the motor lead. The other parallel circuit having been already interrupted at n^1 , n^2 , and as the contact levers o and contacts o^1 are in series, on one or the 45 other of the levers o being displaced out of contact with the respective contact o^1 , current is cut off from the motor, which stops.
- On the clockwork n^4 eventually running down, the bar n^1 makes contact with the 50 spring contact n^2 , which closes the respective parallel motor circuit, and the motor starts. The slats which have been holding back the levers o , then, by the progress of the band, are moved away from these levers, 55 which are returned by springs o^3 to their contacts o^1 , and this parallel circuit is re-established and keeps the motor running when n^1 , n^2 are again separated by a slat forcing back the plunger rod m .
- 60 The momentum of the mechanism causes the band to move a slight distance even after the current has been cut off from the motor.

Hence two switch levers o in series are employed, because one lever o only, set to stop the motor sufficiently ahead of the position at which the band comes to rest when moving in one direction, would stop the motor too late in the other direction. With the two switch levers o , one can be located at the proper position for each direction, and the current is cut off by the first lever o displaced.

When all the posters have been unwrapped from the unwinding roller b^1 or b^2 , a stud p on the terminal slat l at one end 75 of the band a and the last slat l but one at the other end of the band, strikes a sliding tappet q and carries it along in the same direction as the band a is traveling. Thereby a triangular spring-pressed nose q^1 on a 80 rod q^2 , pivoted to the sliding tappet q , displaces a reversing switch lever r , pivoted at r^0 , by riding over a stud r^1 protruding from a lateral arm r^2 of the switch lever r .

When either of the switch levers o is displaced off the contact o^1 , it makes contact with a contact plate o^2 which closes the circuit of the illuminating lamps. The two contacts o^2 are in parallel.

The posters have slats t at each end, to 90 which spring wires t^1 are attached with their ends free. The ends of the wires t^1 are snapped into metal strips t^2 embracing the slats t , thus holding the posters on the band.

I claim:

1. In a poster displaying machine, a band of posters, an electromotor, driving means interconnecting said band and said motor, parallel circuits of said motor, a switch in each said parallel circuit, means for opening one said switch during the passage of each said poster across said machine and for opening the other said switch at the end of said passage and retarded means for closing said first switch after said second switch 105 has been opened.

2. In a poster displaying machine, a roller at opposite ends of said machine, a band of posters led around said rollers, slats between each said poster, an electro-motor, 110 means interconnecting one of said rollers and said motor, parallel circuits of said motor, a switch in one said circuit in the path of said slats, means for delaying closure of said switch and a circuit breaking switch in the other said circuit in the path 115 of said slats.

In testimony whereof I affix my signature in presence of two witnesses.

EDWARD WILLIAM BROWN.
